UNITED STATES PATENT OFFICE.

AMOS F. DIXON AND FRANK N. REEVES, OF NEWARK, NEW JERSEY, ASSIGNEES TO
WESTERN ELECTRIC COMPANY, INCORPORATED, OF NEW YORK, N. Y., A CORPORATION OF NEW YORK.

TELEPHONE-EXCHANGE SYSTEM.

1,340,940.

Specification of Letters Patent. Patented May 25, 1920.

Application filed May 7, 1917. Serial No. 166,839.

To all whom it may concern:

Be it known that we, AMOS F. DIXON and FRANK N. REEVES, citizens of the United States, both residing at Newark, in the county of Essex and State of New Jersey, have invented certain new and useful Improvements in Telephone-Exchange Systems, of which the following is a full, clear, concise, and exact description.

10 This invention relates to a telephone exchange system in which a call originating at one operator's position may be extended over a suitable connecting circuit or trunk to a second operator's position, and in which 15 means are provided at such second operator's position responsive to the operation of a manually controlled device at such first operator's position to exhibit the number of the desired line at such second operator's position.

20 It is an object of the present invention to provide an arrangement of this character which is adapted to be employed in connection with telephone exchange systems of 25 the semi-automatic type in which the exhibiting device may be actuated in response to the operation of a registering and controlling equipment which may be manipulated by an operator in the same manner as 30 the ordinary equipment utilized in controlling semi-automatic switching apparatus. The operator sets up the number on a suitable key board in the same manner in which 35 a number is set up on the keyset of the ordinary registering and controlling equipment, and as will more clearly appear, when thus set, may control the operation of automatic switches to extend a connecting circuit to a trunk circuit leading to a manual 40 operator's position, and also may control means for exhibiting the desired number at such manual operator's position.

In accordance with a feature of this invention, a printing device is provided at a manual operator's position which is adapted to 45 automatically operate in response to the operation of a registering and controlling equipment at another operator's position to print the number of the desired line as determined by the operation of the manually operable device.

In accordance with a further feature of the invention, there is provided a printing device at an operator's position, together

with means for automatically associating such printing device with a trunk line or connecting circuit upon which the call is awaiting attention, and such printing device is adapted to print a character indicating the particular trunk with which the 60 printer has been automatically associated.

In accordance with another feature of the invention, the indicating or recording device which, as far as certain features of the invention are concerned, may either be a 65 printer, which is the preferred device, or any form of visual indicator, is adapted to be controlled by means of code impulses, the preferred arrangement being a code form of various combinations of five positive or 70 negative current impulses. These impulses are produced by means of registers which form a part of a registering and controlling equipment of known type, and which are adapted to be set in various positions in response to the operation of certain number 75 keys. These registers are set in response to the operation of the keys in identically the same manner as when the registers are to be utilized in controlling the operation of 80 automatic switches, but in accordance with this feature of the invention, such registers are arranged so that after the registering and controlling equipment has been associated with the indicating or printing device, each register is successively and automatically driven through a plurality of additional positions, and, in moving through such additional positions, places upon a controlling circuit extending between the registering and controlling equipment and the indicator the particular combination of impulses necessary to cause the indication or printing of the number or character represented by the set position of the registers. 95

In accordance with another feature of the invention, the printer or indicator, as the case may be, is arranged so that when the number has been printed or indicated, a suitable signal controlled from such printer 100 or indicator is displayed before an operator to inform such operator that the call indicated or printed is waiting attention on the particular trunk with which the signal is associated. In accordance with a related 105 feature of the invention, means are provided for the purpose of changing the character of this signal in case the operator has

not disconnected the particular trunk when such particular trunk has been previously used in establishing another connection.

In accordance with another feature of the invention, means are provided in case the initial digit of the number which it is desired to indicate or record is 0, to automatically eliminate the corresponding recording or indicating operations.

10 In accordance with another feature of the invention, means are provided whereby, in case the number which it is desired to record or indicate is large, more than one digit may be automatically recorded and indicated without the necessity of an additional recording or indicating operation.

In the accompanying drawings, Figures 1 and 2 represent diagrammatically an A operator's connecting circuit and associated apparatus; Figs. 3, 4, 5 and 6 represent diagrammatically a registering and controlling equipment and associated apparatus; Fig. 7 represents diagrammatically a recording device adapted to be associated with a connecting circuit at a B operator's position; and Fig. 8 represents one of such B operator's connecting circuits.

The complete system is shown with Fig. 2 beneath Fig. 1, Fig. 3 beneath Fig. 2, Fig. 4 beneath Fig. 3, Fig. 5 to the right of Fig. 3, Fig. 6 to the right of Fig. 4 and beneath Fig. 5, Fig. 8 to the right of Fig. 2 and Fig. 7 above Fig. 8.

In the system disclosed, there is shown in Fig. 2, a connecting circuit of an A operator's position, terminating in a plug. When a call is initiated at such position, it is only necessary for the A operator to insert the plug in the jack of calling line in order that her telephone may be automatically connected to a particular connecting circuit by means of the automatic listening key, and associated apparatus shown in Fig. 1. When the operator has ascertained the number of the desired line, she has only to set up this number on the keys of the registering and controlling equipment indicated in Figs. 5 and 6 in order to automatically control the extension of the particular connecting circuit to a trunk leading to a manual operator's position in another exchange or at the same exchange shown in Fig. 8, and to also cause the printer disclosed in Fig. 7 to print the number of the desired line; and also the number of the particular trunk shown in Fig. 8. The registering and controlling equipment shown in Figs. 4, 5 and 6 is automatically associated with the connecting circuit by means of the cord finders shown in Fig. 3, one of which is allotted for use with the next incoming call by means of the allotter also shown in Fig. 3. The selector switch which is utilized to extend the connecting circuit to the printer is of the type which is disclosed in United

States Patent No. 1,168,319 issued January 18, 1916, to Alben E. Lundell. The cord finder and allotter are also of similar construction to the cord finder and allotter shown in such patent. The registers shown in Figs. 5 and 6, forming a part of the registering and controlling equipment, are of the same mechanical construction as the registers disclosed in United States Patent No. 1,168,319 issued January 18, 1916, to Alben E. Lundell, as are also the counting relays shown in Fig. 4. The sequence switches shown in the various figures coöperating with various parts of the system are of the type disclosed in United States Patent No. 1,127,808 issued February 9, 1915, to John N. Reynolds and Charles F. Baldwin, and the contacts operated by said sequence switches are in every case designated by reference numerals having the same initial digit as the reference character utilized to designate the power magnet of the corresponding sequence switch.

In referring to these sequence switch contacts in the specification, in order to avoid needless repetition, they will be referred to merely by the word "contact" followed by the reference character which is employed to designate them, and in parenthesis by the word "position" and a numeral indicating the particular position in which the sequence switch is located at the time.

Referring now to Fig. 7, the switch indicated by the numeral 700, which is adapted to hunt for a trunk upon which a call has been extended and to connect a printer in operative relation thereto, is of the type known as a finder switch. This switch may be of any well-known type and is indicated as comprising a shaft 714, carrying an arm 704, which is adapted to be moved over terminals leading to trunks as long as the clutch magnet indicated at 701 is energized. This switch, however, carries upon the shaft a type wheel indicated at 715, which type wheel is provided with a character corresponding to each of the trunks, which character is adapted to be brought opposite the printing hammer 717 of the printing magnet 711 when the brushes carried by the arm 704 have been stopped on the terminals of the trunk. A suitable mechanism, not shown, is provided for presenting a strip of paper or other recording medium between the type wheel and the hammer 717. The distributing switch, shown in the dotted rectangle in Fig. 7, is of the type disclosed in United States Patent No. 1,215,917, issued February 13, 1917, to O. A. Danielson and the printer, which is diagrammatically shown also in Fig. 7, is disclosed in United States Patent No. 1,201,809 issued October 17, 1916, to Amos F. Dixon, to which reference may be had for the details of construction. Although the apparatus as outlined

above is the type of apparatus which it is preferred to use to carry out the invention, it is obvious that equivalent apparatus could be substituted without departing from the spirit of the invention, and as far as certain features of the invention are concerned any type of apparatus adapted to be operated to display or indicate in any manner the designation of the call may be employed.

Printers of the type disclosed in the above mentioned patents are adapted to operate in response to different combinations of five positive or negative current impulses. When the printer is adapted for use as a call number indicator all possible combinations need not be used, as the ordinary call number can be recorded by means of a small number of characters, for example, in the system disclosed no call number exceeds five digits and a party designating character. Five digit numbers may be printed in four printing operations as will more clearly appear hereinafter, and, as will be apparent from the specimen code given below, the maximum number of characters required in the system disclosed being seventeen.

	<i>Number or character.</i>	<i>Impulse combination.</i>
30	0	— + — —
	1	— + — —
	2	+ — — —
	3	— — — —

	Party J	— + — +
45	" M	+ — + —
	" R	— + — +
	" W	+ — — +

It is obvious that any of the above characters could be replaced by letters or arbitrary signs on the type wheel if desired.

As soon as the operator observes the calling lamp and inserts the plug 203 into the answering jack of the calling line a circuit is established for relay 201, which circuit extends from battery on the sleeve of the jack through sleeve of the plug 203, conductor 204, contact 101 (position 1), relay 201 to ground. Relay 201 closes at its left armature and front contact a circuit for the listening key sequence switch 100 which circuit extends from battery through motor magnet of the listening key sequence switch 100, contact 102 (position 1), conductor 103, front contact of the relay 201 to ground,

whereupon the sequence switch 100 moves into position 7.

In position 7 of the listening key sequence switch the operator's telephone set is connected in operative circuit relation with the calling line, which circuit may be traced from the tip side of the calling line through the tip of the jack 203, conductor 205, contact 104 (position 7), conductor 105, conductor 106, the operator's telephone (not shown) and from thence by conductor 107, conductor 108, contact 109 (position 7), conductor 206 to the ring side of the calling line. Battery for conversational purposes is placed upon this circuit from the ungrounded side of the 80 battery through the winding 207 of the repeating coil, conductor 208, contact 110 (position 7), conductor 111 and then by conductor 107 to the telephone set of the operator, and by conductor 108 to the telephone of 85 the calling subscriber, and then back from the operator and the subscriber by conductors 106 and 105, respectively, to the conductor 112, contact 113 (position 7), conductor 209 to the winding 210 of the repeating coil to the grounded side of the battery. Thus the operator is enabled to converse with the calling subscriber and ascertain the number desired.

In position 7 of the sequence switch 100 a 95 circuit is established to drive the district sequence switch 200 into position 2, which circuit extends from battery to the motor magnet of sequence switch 200, conductor 211, conductor 212, contact 101 (position 7), 100 conductor 213, contact 214 (position 1) to ground. With the district sequence switch 200 in position 2 a circuit is established for the relay 301, which extends from battery to the relay 301, contact 304 in position 1, 105 conductor 215, contact 114 (position 7), conductor 216, contact 214 in position 2 to ground. The relay 301 closes at its right-hand armature and contact a circuit to drive the cord finder sequence switch 300 into position 2, which circuit extends from battery to the motor magnet of the sequence switch 300, contact 305 (position 1), front contact and right-hand armature of the relay 301 to ground. At the right of Fig. 3 115 within the dotted rectangle an allotter of the type disclosed in United States Patent 1,168,319 issued January 18, 1916, to Alben E. Lundell is diagrammatically shown. This allotter serves to allot a cord finder 120 switch for use with the next incoming call by causing the cord finder sequence switch of the cord finder allotted to move from position 18 to position 1. As the allotter forms no part of the present invention it will not 125 be further described and it will be assumed that the cord finder shown in Fig. 3 has been allotted and that the corresponding sequence switch 300 has been moved to position 1 previous to the initiation of the particular call 130

the progress of which is being traced. When the sequence switch 300 reaches position 2 a circuit is closed for the up-drive magnet 302 of the cord finder, which circuit extends from battery through up-drive magnet 302, contact 306 (position 2), front contact and right-hand armature of the relay 301 to ground. The original energizing circuit for the relay 301 is interrupted as 5 the sequence switch moves out of position 1 $\frac{1}{2}$. Such relay is maintained energized over either of two substitute circuits, one of which extends from battery, relay 301, front contact and left armature thereof to the 10 commutator C and by way of the interrupter brush 307 to ground, while such interrupter brush is passing over segments of the commutator C of the cord finder, and the other of which extends from battery to the relay 15 301, contact 304 (position 2) to the back contact and right-hand armature of the relay 303 to ground. Therefore, while the test brush 308 of the cord finder passes over terminals of cords which have not been 20 taken for use, the relay 301 will be maintained energized. As soon as the particular cord which has been taken for use is encountered, a circuit is established from test relay 303, which circuit extends from battery 25 to the relay 303, contact 309 (position 2), test brush 308, conductor 217, contact 114 (position 7), conductor 216, contact 214 (position 2) to ground.

It will be observed that the ground which 30 makes the connecting circuit in Fig. 2 selectable in the cord finder extends by way of a contact of the district switch 200 and by a contact of the listening sequence switch 100.

The relay 303, when energized, opens at 35 its right-hand armature and back contact one of the energizing circuits of relay 301, and when the other energizing circuit for the relay 301 is opened at the commutator C when the cord finder brushes are centered 40 upon the selected terminals, the relay 301 deenergizes, opening the circuit previously traced for the up-drive magnet 302, and thereby stopping the upward movement of the cord finder. The deenergization of relay 45 301 also closes a circuit to drive the cord finder sequence switch to position 3, which circuit extends from battery to the motor magnet of the sequence switch 300, contact 305 (position 2), back contact and right 50 armature of the relay 301 to ground. The relay 303 is held up and thus prevents the re-energization of the relay 301 until the sequence switch 300 has reached position 3 by a circuit which extends from battery through 55 relay 303, contact 309 in positions 2 to 2 $\frac{1}{2}$, front contact and right-hand armature of relay 303 to ground. The relay 303 is also held up when the sequence switch 300 reaches position 3 by a circuit which extends from 60 battery to the contact 309 in position 3, left- 65

hand armature and front contact of relay 303, brush 310, conductor 218, contact 219 in position 2, to the back contact and left-hand armature of the relay 202 to ground.

In the meanwhile the operator has set up 70 the number of the desired line on her keyboard, which will be assumed was North 11-5-4-9-J. It will also be assumed that the North office is a manual office. As will more clearly appear in response to the depression 75 of the office key 501 of Fig. 5, which is assumed to be the North office key, the office selector will select a trunk leading to a B operator's position at such North office, and the depression of the keys representing No. 80 11-5-4-9-J shown in Fig. 6 will cause the operation of the printing device shown in Fig. 7 associated with the B operator's position for the purpose of printing the required number at such B operator's position. For 85 convenience and in order to prevent undue complication in the drawings, only one office key and one thousands, hundreds, tens and units key are shown, the key shown in each case being assumed to be that which is depressed to represent North 11-5-4-9-J. These 90 keys are of the type which are mechanically locked and adapted to be released electrically as will presently appear.

As soon as the office key 501 has been depressed, a circuit is established from battery through contact 311 (position 3), allotter contact 1 in position 1, allotter contact 2 (position 1), the relay 3, allotter contact 4 in position 1, conductor 502, relay 503, relay 100 504, contact of the key 501, relay 505 to ground. The operation of relay 3 is of no consequence at the present stage of circuit connections, and its function in a subsequent connection will be hereinafter described. 105 The operation of the relays 504 and 505 placed ground upon the contacts 506 and 507 of the district registers, respectively, and the relay 503 closes the energizing circuits 110 for the motor magnets 508 and 509 of such registers. These circuits may be traced from battery, contact 312 (position 3), and by conductors 510 and 511 in parallel, the magnets 508 and 509, back contacts of cut-off relays 512 and 513, conductor 514, armature 115 and contact of relay 503 to ground.

Therefore, as soon as the cord finder sequence switch reaches position 2, the district registers may be started on their registering movement. As soon as the district registers 120 reach position 16, which is the position in both registers which it is assumed will cause the selection of the North office, circuits are established for the register cut-off relays 512 and 513, which circuits extend from battery 125 through the contact 311 (position 3), allotter contact 1 (position 1), allotter contact 2 (position 1), relay 3, allotter contact 4 (position 1), conductors 514 and 515 in parallel and through the cut-off relays 512 and 513 to 130

the register contacts 506 and 507 which are closed when the registers reach position 16, to the armatures and contacts of energized relays 504 and 505 to ground.

- 5 The relays 512 and 513 when energized open the previously traced energizing circuits for the register power magnets 508 and 509, causing both registers to stop in the case assumed in position 16. Relays 512 and
- 10 513 also close a circuit to drive the cord finder sequence switch 300 into position 4, which circuit extends to battery through the motor magnet of the sequence switch 300, contact 313 (position 3), conductor 516, left armature and contact of relay 512, front contact and armature of the relay 513, conductor 514, contact and armature of the relay 503 to ground. When the sequence switch 300 reaches position 4, a circuit is est-
15 20 25 30 35 40 45 50 55 60 65
- ablished to drive the sender sequence switch 400 into position 2, which circuit extends from battery through motor magnet of the sequence switch 400, contact 401 (position 1), conductor 402, contact 314 (position 4), to ground. As in the case assumed, it is only necessary to employ a single selector switch to select a trunk leading to the manual office. The sequence switch 300 is arranged to move directly into position 5 without stopping at position 4, the circuit for driving sequence switch 300 into position 5 extending from battery through motor magnet of the sequence switch 300, contact 313 (position 4), to ground. However, with the sequence switch 300 in either position 4 or position 5 and the sequence switch 400 in position 2 and sequence switch 200 in position 2, the fundamental circuit is established for the purpose of controlling brush selection in the selector switch shown in Fig. 2. It will be remembered that the registers shown in Fig. 5 have been set in position 16, and, as indicated in the lower part of Fig. 5, the register contact 517 has closed a circuit leading to the No. 1 counting relay shown in Fig. 4, and the register contact 518 has closed a circuit to the No. 7 counting relay. These counting relays are of the well-known type such as is disclosed in the United States Patent No. 1,168,319 issued January 18, 1916, to Alben E. Lundell and operated in the same manner as in such patent so that when the No. 1 counting relay is energized, the counting relays will control the production of two impulses in the fundamental circuit, and when the No. 7 counting relay is energized such counting relays will control the production of eight impulses in the fundamental circuit.
- 60 The fundamental circuit which is established at this time may be traced from battery through line relay 220, contact 221 (position 2), conductor 222, terminal 315, brush 316, conductor 317, contact 318 (position 4), conductor 319, contact 403 (position 2), con-
ductor 404, stepping relay 405, back contact and armature of the number 0' counting relay, conductor 406, front contact and right-hand armature of the relay 303 to ground. The relays 405 and 220 are energized in this circuit. The energization of the relay 220 establishes a circuit to drive the sequence switch 200 into position 3, which circuit extends through the motor magnet of sequence switch 200 through contact 225 (position 2), front contact and left-hand armature of the relay 220, back contact and right armature of the relay 202 to ground. The relay 405 when energized establishes a circuit to energize the No. 1 counting relay, which circuit extends from battery through No. 1 counting relay, back contact of the No. 1' counting relay, register contact 517, conductor 519, contact 407 (position 2), conductor 408, armature and contact of the stepping relay 405 to ground. The relay 220, when the sequence switch 200 reaches position 3, closes a circuit for the up-drive magnet 224 of the selector switch, which circuit may be traced from battery through magnet 224, contact 225 (position 3), front contact and left armature of the relay 220 back contact of the right armature of relay 202 to ground. As the interrupter brush 295 passes over the segments of the A commutator of the selector due to the upward movement of the elevator rod 226, a shunt circuit for relay 405 is closed, which shunt circuit extends from battery through relay 220, contact and right armature of relay 220, contact 227 (position 3), contact 228 (position 3), to the A commutator of the selector switch, brush 295, contact 229 (position 3) to ground. As the No. 0' counting relay is energized after two such shuntings of the stepping relay 405, the fundamental circuit is opened by the energization of the No. 0' counting relay. The opening of the fundamental circuit causes the release of the line relay 220 when the brushes of the selector are properly centered, and, consequently, the opening of the previously traced circuit for the up-drive magnet 224. The release of the line relay 220 also establishes a circuit to drive the sequence switch 200 into position 4, which circuit extends from battery, through the motor magnet of sequence switch 200, through contact 230 (position 3), back contact and left armature of relay 220, back contact and right armature of relay 202 to ground.
- 65 In position 4 of the sequence switch 200 a circuit is established for the trip magnet 231, which circuit extends from battery, through the trip magnet contact 232 (position 4) to ground. As the trip magnet has been thus energized after two shuntings of the stepping relay, when the elevator rod is again set in motion, as will be hereinafter described, the second set of brushes of the

selector switch will be tripped, and it will be assumed for the purpose of illustration, that the set of brushes shown associated with the elevator rod is the set tripped. When 5 the No. 0' counting relay opened the fundamental circuit as above described, it also closed at its front contact a circuit to drive the sender sequence switch 400 out of position 2 and into position 4. This circuit 10 extends from battery, through the motor magnet of sequence switch 400, contact 408 (position 2), front contact and armature of the 0' counting relay, conductor 406 to ground at the right armature and front contact of relay 303. With the sender sequence switch 400 in position 4 and the cord finder sequence switch 300 in position 4, and the sequence switch 200 in position 4, the fundamental circuit is again established which 15 now extends from battery, line relay 220, contact 221 (position 4), conductor 222, terminal 315, brush 316, conductor 317, contact 318 (position 4), contact 403 (position 4), conductor 404, stepping relay 405, armature and back contact of the No. 0' counting relay, conductor 406, front contact and right armature of the relay 303 to ground. The energization of the relay 220 at this 20 time drives the sequence switch 200 into position 5 over a circuit which extends from battery, motor magnet of sequence switch 200, contact 225 (position 4), front contact and left-hand armature of relay 220, back contact and right armature of relay 202 to ground. With the sequence switch 200 in 25 position 5, a circuit is again closed for the up-drive magnet 224, which extends from battery through the magnet 224, contact 225 (position 5), front contact and left-hand 30 armature of the relay 220, back contact and right armature of relay 202 to ground. As the elevator shaft 226 moves upward the set 35 of brushes are tripped, and when the brush 233 makes contact with the segments of the commutator B, a shunt circuit is established which intermittently shunts the stepping relay 405. This shunt circuit extends from battery, through relay 220, front contact and right-hand armature thereof, contact 227 (position 5), contact 228 (position 5), commutator B, brush 233 to ground at contact 229 (position 5).

Upon the first energization of relay 405 a circuit is established for the No. 7 counting relay, which circuit extends from battery, through the No. 7 counting relay, back contact of the No. 7' counting relay to the register contact 518, conductor 520, contact 407 (position 4), conductor 408, armature 40 and back contact of stepping relay 405 to ground. The counting relay sets 5 and 5' to 8 and 8' inclusive have been omitted from the drawing to avoid needless duplication, and as the function of all sets of counting 45 relays is identical, the above current through

counting relay set 7 and 7', although not shown, should readily be understood. After the stepping relay 405 has been energized and deenergized eight times, No. 0' counting relay is energized in the usual manner 70 and opens the fundamental circuit. The opening of the fundamental circuit causes the relay 220 to release when the brushes are centered on the terminals, and hence the shunt circuit by way of the commutator 75 B is open, and such relay when released closes a circuit to drive the sequence switch 200 into position 6, which circuit extends from battery, through the motor magnet of sequence switch 200, conductor 211, contact 80 230 (position 5), back contact and left-hand armature of the relay 220, right armature and back contact of relay 202 to ground. The No. 0' counting relay also closes at its front contact, a circuit to drive the sequence 85 switch 400 into position 5, which circuit extends from battery, through the motor magnet of the sequence switch 400, contact 408 (position 4), front contact and armature of the 0' counting relay, conductor 90 406, front contact and right-hand armature of relay 303 to ground.

As the sequence switch 200 reaches position 6, a circuit is established for the test relay 234. This circuit extends from battery, through the upper winding of the test relay 234, contact 235 (position 6), to ground. Relay 234 when energized closes a circuit to drive the sequence switch 200 into position 7, which circuit extends from battery, through the sequence switch 200, contact 225 (position 6), front contact and upper armature of relay 234, back contact and right armature of relay 202 to ground. When the sequence switch 200 reaches position 7, a circuit is established for the up-drive magnet 224, which circuit extends from battery, through the magnet 224, contact 225 (position 7), front contact and upper armature of relay 234 to ground at 100 the back contact and right-hand armature of the relay 202. The brushes are thereupon moved over the group of terminals selected for the purpose of hunting for an idle trunk in such group leading to the required office.

If a trunk is idle, the test terminal 236 in all district selectors in which it appears will be without potential. If, however, the trunk individual to the terminal 236 is occupied, 120 having been seized by another district selector, a ground will be placed upon such terminal by way of the test brush 237, conductor 238, back contact and lower armature of test relay 234, contact 219 (position 6½ to 16½), 125 back contact of relay 202 of the district selector in connection with the trunk of the particular time, to ground. Therefore, in any given case, as long as the test brush 237 of the district selector passes over terminals 130

236 individual to trunks which have been seized by other district selectors, there will be a ground upon such test terminals and the relay 234 will be maintained energized over a circuit which extends from battery, through the lower winding of relay 234, front contact and armature thereof, conductor 238, test brush 237, test terminal 236 to ground. In order to maintain the relay 234 energized while the brush 237 is passing between terminals, a substitute energizing circuit is maintained for said relay over a circuit which extends from battery, through the upper winding of relay 234, contact 235 (position 7), the C commutator, brush 239, contact 225 (position 7), front contact and upper armature of relay 234 to the back contact and right-hand armature of relay 202 to ground. When the test brush 237 reaches a terminal 236 which is individual to an idle trunk, which it will be assumed is the trunk shown in Fig. 8, as soon as the brushes are centered upon the terminals thereof, both energizing circuits previously traced for the relay 234 will be opened, causing the relay 234 to release. Relay 234 when released opens the circuit of the up-drive magnet 224 and hence stops the selector with the brushes on the terminal of an idle trunk. The relay 234 when released also closes a circuit to drive the sequence switch 200 into position 8, which circuit extends from battery, through the motor magnet of sequence switch 200, contact 248 (position 7), back contact and upper armature of the relay 234, back contact and right-hand armature of the relay 202 to ground.

In position 8 of the sequence switch 200 a circuit is established to drive the sequence switch 400 from position 5 to position 9, which circuit extends from battery, motor magnet of sequence switch 400, contact 401 (position 5), conductor 409, contact 320 (position 5), conductor 321, brush 322, terminal 323, conductor 240, contact 232 (position 8), to ground. The intermediate positions from 5 to 9 of the sender sequence switch 400 are utilized only in case it is desired to bring about other selections than those necessary in the system illustrated. For example, if the selector switch shown in Fig. 2 selected a trunk leading to a second selector switch and such second selector switch was utilized to select a trunk leading to a manual office, the intermediate positions could be used. When the sender sequence switch 400 passes through positions 6 to 8, a circuit is established to energize the line relay 220, which circuit extends from battery, through the line relay 220, contact 221 (position 8), contact 227 (position 8), conductor 241, terminal 324, brush 325, conductor 326, contact 410 (positions 6 to 8) to ground. The line relay 220 when energized closes a circuit to drive the sequence switch 200 to position 11. This circuit extends from battery through the motor magnet of the sequence switch 200, contact 225 (position 8), front contact and left-hand armature of the relay 220, right-hand armature 70 and back contact of relay 202, to ground.

While the various selecting operations above described have been taking place for the purpose of associating the connecting circuit with a trunk leading to the manual office, the number registers, shown in Fig. 6, may be moved to their set position as determined by the particular keys depressed. These registers are of the type employed in the United States Patent No. 1,168,319 issued January 18, 1916, to Alben E. Lundell, but as will more clearly appear hereinafter such registers are arranged to operate in a different manner, and for a different purpose. As the registers are for the purpose of controlling the production of code impulses for the operation of the printing device, such code being formed of combinations of five positive and negative current impulses, the registers are not limited to ten setting positions, because it is possible to obtain several more than ten different code combinations with five impulses, and, therefore, the type wheel of the printer, instead of having merely numbers from zero to nine, may be provided with numbers from ten to fifteen or even twenty-five. By suitably arranging the register, it is possible to print a five digit number in response to four sets of code impulses, or what amount to the same thing, by the employment of four registers, as two digits may be printed in response to a single set of impulses.

In the system disclosed, for example, it will be assumed that it is desired to print numbers up to twelve thousand. Therefore, the thousands register is adapted to be controlled by two sets of keys, there being one set of keys from zero to nine which are operated when it is desired to register zero to nine, and a separate key which is depressed only in case the number which it is desired to register is more than nine thousand. One of the thousands keys is indicated in Fig. 6 by the reference character 600, this being, as shown, the number one thousand key. The ten thousands key is indicated at 601. Therefore, in order to set the register in the position to register eleven thousands, or in other words the eleventh position, the key 601 is first depressed and then a key 600, it being apparent from an inspection of the keys associated with the thousands register, in case the key 600 is depressed without the key 601 being depressed, the energizing circuit for the register cut-off relay 602 will extend through the normal contact of the key 601 to the register spring 605 (position 1), the key 600 and battery. Whereas, if the key 601 is depressed, the energizing circuit of the 130

register cut-off relay 602 will be by way of the register spring 604. The station register is also arranged somewhat differently from the registers shown in the prior art, there being 5 utilized fourteen positions although there are only five stations. The contacts and keys are arranged so that with the key marked direct depressed a station register will stop in either position zero or nine, the 10 key marked J in position 1 or 10, the key marked M in position 2 or 11, the key marked R in position 3 or 12, and the key marked W in position 4 or 13. This arrangement is utilized because the registers have 15 no normal position, and as will hereinafter appear, it is necessary for the register to move in all cases through five positions beyond its setting position. Therefore, in order to limit the extent of the travel of the 20 register in response to the depression of the next key, two positions are provided on the register individual to each key, which positions are spaced apart nine positions, which is the maximum number of positions utilized 25 in setting and controlling movement of the station register in response to the depression of any key. In the particular instance which is about to be described, it has been assumed that the ten thousands key 601 has 30 been depressed, the number one thousands key indicated at 600 has been depressed, the number five hundreds key indicated at 605, the number four tens key indicated at 606, the number 9 units key indicated at 607 and 35 the number J station key indicated at 608. Each of the keys of the station register, which are the last keys depressed in setting up a number, operates, when depressed, a contact indicated at 609. This contact closes 40 a circuit for the start relay 610, provided the cord finder is in position 1 to 5. This circuit extends from battery (Fig. 3), contact 311 on the cord finder (positions 1 to 5), allotter contact 1 (position 1), allotter contact 2 (position 1), allotter relay 3, allotter contact 5 (position 1), conductor 521, start 45 relay 610, to the contact 609 to ground. Relay 610 when energized established circuits for the power drive magnets 622, 623, 50 624, 625 and 626 of the thousands, hundreds, tens, units and station registers, respectively. These circuits extend from battery (Fig. 3), by way of contacts 312 and 327 (positions 2 to 6), and thence in parallel over conductors 411, 412, 413, 414 and 415 to the motor magnets 622, 623, 624, 625 and 626 to inner armature and back contacts of relays 602, 630, 631, 632 and 633, to conductor 611, front contact and inner armature of relay 610 55 to ground. When the thousands register reaches position 11, the hundreds register reaches position 5, the tens register reaches position 9 and the station register reaches position 1 or 10, circuits for the register cut-off relays 602, 630, 631, 632 and 633 are es-

tablished as follows: from battery, contact spring 311 (position 5), allotter contact 1 (position 1), allotter contact 2 (position 1), relay 3, allotter contacts 5 and 6 (position 1), and thence in parallel by conductors 522, 523, 524, 525 and 526 to register cut-off relays 633, 632, 631, 630 and 602, respectively, and thence by way of key 601, thousands register spring 604, key 600 to ground, hundreds register spring 641, key 605 to ground, 75 and tens register spring 635 and key 606 to ground, units register spring 636, key 607 to ground, and station register spring 637, key 608 to ground.

Due to the energization of the register 80 cut-off relays at this time, the previously traced circuits for the register power magnets are opened and the thousands register is stopped in position 11, the hundreds register in position 5, the tens register in position 85 4, the units register in position 9 and the station register in position 1 or 10. The register cut-off relays when energized also close a series circuit to drive the cord finder sequence switch 300 into position 6, which 90 circuit extends from battery through the motor magnet of sequence switch 300, contact 313 (position 5), conductor 527, outer armatures and front contacts of the relays 602, 630, 631, 632 and 633, inner armature 95 and contact of the relay 610 to ground.

In position 6 of the sequence switch 300, a circuit is closed for the released magnets, which when operated release all of the depressed keys of all of the registers, there 100 being four of these release magnets diagrammatically shown in Fig. 5 and indicated at 528. The energizing circuits for these release magnets extend from battery through the contact 328 (positions 6 to 6½), 105 and thence in parallel to the release magnets 528 to ground. If all of the keys are restored by the operation of the release magnets, the relay 3, which was energized in all of the circuits traced through the keys, will 110 be deenergized, driving the sequence switch 300 into position 7 over a circuit which extends from battery to the motor magnet of the sequence switch 300, contact 305 (position 6), back contact and right-hand armature 115 of the relay 3 to ground.

When the sequence switch 300 reaches position 7 a circuit is closed for the allotter power magnet 10, which extends from battery to the magnet 10, contact 329 (position 7), allotter contact 8 (position 1), to ground. The allotter thereupon operates in the usual manner to allot another cord finder for use in connection with the next call.

As the sender sequence switch 400 reached position 9, as above described, while the number registers were being set, the cord finder sequence switch 300 is advanced to position 8 by a circuit which extends from 130

battery through the motor magnet of the sequence switch 300, contact 331 (position 7), conductor 332, contact 410 (position 9), to ground. With the sequence switch 200 5 in position 11, sequence switch 300 in position 8, and sequence switch 400 in position 9, a circuit is established for the relay 800 associated with the trunk which has been selected for use, which circuit extends from 10 battery, through the left-hand winding of relay 412, contact 436 (position 9), conductor 437, contact 318 (position 8), conductor 317, brush 316, terminal 315, conductor 222, contact 221 (position 11), contact 227 (position 11), brush 243, terminal 242, trunk conductor 801, upper armature and back contact of relay 805, relay 800, to the back contact and armature of the relay 802 to ground. The relay 412 closes at its 20 outer armature and front contact a circuit to drive the sequence switch 300 into position 9, which circuit extends from battery through motor magnet of the sequence switch 300, contact 333 (position 8), conductor 334, front contact and outer armature of the relay 412 to ground. The energization of the relay 800 closes a circuit to start the switch indicated at 700 to hunt for the trunk which has been taken for use 30 and to connect thereto the printer shown diagrammatically in Fig. 7. The circuit established by the energization of relay 800 for the clutch magnet of the sequence switch 701 extends from battery through 35 the outermost armature and back contact of the test relay 702, clutch magnet 701, conductor 703, front contact and inner armature of the relay 800 to ground. As soon as the clutch magnet 701 is energized, the 40 arm 704 is moved by mechanism (not shown) to cause the brushes 705, 706 and 707 to pass over terminals individual to a plurality of trunks with which the printer may be used. As soon as a set of contacts 45 708, 709 and 710, individual to the trunk shown in Fig. 8, which has been taken for use, is reached, a circuit is established from battery, left-hand winding of test relay 702, printer magnet 711, brush 705, contact 708, conductor 712, the outer armature and contact of the relay 800 to ground. The relay 702 when energized closes at its inner armature a locking circuit for itself, which circuit extends from battery, printer contact 50 55 736, conductor 737, inner armature and contact of relay 702, right-hand winding of relay 702 to ground.

Relay 702, when energized, opens at its outermost armature the energizing circuit 60 for the clutch magnet 701 and stops the switch with the brushes 705, 706 and 707 in position to make contact with the desired trunk. The magnet 711 is also energized at this time for the purpose of recording the 65 number of the trunk with which the printer has been associated. As shown in Fig. 7 of the drawing the shaft 714, which carries the arm 704, also carries a type wheel 715. A strip of paper indicated at 716 is adapted to be presented by any suitable mechanism 70 between the type wheel 715 and the plunger 717. The type wheel carries suitable characters or numbers which are spaced about the plunger and the type wheel in the same relation as the trunks are connected to the 75 stationary contacts of the switch, so that when the plunger 717 is actuated, a record will be made upon the strip of paper 716 corresponding to the particular position of the arm 704, and hence to the particular 80 trunk which is being utilized. As soon as the relay 702 is energized, after the switch 700 has found a trunk, a circuit is established for the relay 802, which circuit extends from battery through the normal contact of relay 803, relay 802, conductor 718, terminal 710, brush 707, to ground at the middle armature of the relay 702. The relay 802 closes also a circuit for relay 805, from battery, normal contact of relay 803, 90 relay 802, left-hand armature and contact thereof, upper winding of relay 805 to ground. The relay 805 does not operate as it is short-circuited by the ground at the armature of relay 702. The energization of 95 the relay 802 opens the circuit previously traced for the relays 800 and 412, both of which are deenergized. Relay 412, when deenergized, closes a circuit to drive the sequence switch 300 to position 10, which circuit extends from battery through the motor magnet, sequence switch 300, contact 330 100 (position 9), conductor 337, back contact and armature of relay 412 to ground.

With the sequence switch 300 in position 105 10, and sequence switch 400 in position 9, relay 412 and relay 405 are energized over a circuit extending from battery, through the left-hand winding of relay 412, contact 436 (position 9), conductor 437, contact 318 110 (position 10), contact 403 (position 9), conductor 404, stepping relay 405, back contact of the No. 0' counting relay, conductor 406, contact and right-hand armature of relay 303, to ground. The energization of the relay 412 at this time closes a circuit to drive the sequence switch 400 in position 10, which circuit extends from battery, through the motor magnet of sequence switch 400, contact 401 (position 9), conductor 335, contact 333 (position 10), conductor 334 to front contact and outermost armature of relay 412 and ground. With the sequence switch 400 in position 10, a circuit is closed 115 for the power magnet 622 of the thousands register, which circuit extends from battery, contact 613 (position 1), conductor 416, contact 417 (position 10), conductor 411, power magnet 622 of the thousands register, 120 back contact and innermost armature of the 125 130

register cut-off relay 602, conductor 418, contact 419 (position 10), conductor 335, contact 333 (position 10), conductor 334, the front contact and outermost armature of the relay 412 to ground. As the thousands register rotates, the contact 614 is closed between each position, thus connecting ground to the energizing circuit of the relay 412 and relay 405 at a point between such 5 relays, thereby shunting the stepping relay 405. This shunt circuit extends from the contact 403 (position 10) by way of conductor 419 to the register spring 614 and thus to ground. Therefore, for each 10 position the register 622 passes through, the stepping relay 405 will be energized and de-energized, and for each energization and de-energization of the relay 405, a pair of 15 counting relays will be energized. It should be observed that in position 10, the contact 420 is closed, and thus establishes an energizing circuit for the No. 4 set of counting 20 relays, which energizing circuit extends from battery through the No. 4 counting relay, armature and back contact of the No. 4' 25 counting relay, contact 420, conductor 408 to the armature and contact of relay 405, so that for the first energization of the relay 405, the No. 4' relay will be energized, and 30 after the fifth operation of the stepping relay 405, the No. 0' counting relay will be energized. Thus, the register 622 will have taken five steps when the No. 0' counting 35 relay is energized and opens the energizing circuits for the relay 412 and the relay 405, thus stopping the register. Before considering the effect of opening the circuit for the relay 412 at this time, the operation of the thousands register in controlling the printer 40 will be described. With the sequence switch 200 in position 11, the sequence switch 300 in position 10, and the sequence switch 400 in position 10, the printer control circuit extending between the registers and the 45 printers is established. This circuit extends from either positive or negative battery, depending upon the particular register springs which are operated, thence by conductors 421, 422, 423 and 424 to the contact 425, or 50 by way of the conductor 426 to contact 427 and from contacts 425 and 427 to conductor 428, the particular path from the negative and positive batteries to conductor 428 depending upon the position at any given time 55 of the register contact springs, and the sequence switch 400. From conductor 428, the printer control circuit extends to conductor 326, brush 325, terminal 324, conductor 241, contact 244 (position 11), conductor 245, brush 246, terminal 247, trunk conductor 804, back contact and lower armature of relay 805, conductor 719, terminal 709, brush 706, to either the positive or negative polarized relays indicated at 60 720 and 721. As it was assumed that the thou-

sands register was set in position 11, positive battery is placed on the printer control circuit and as it passes position 12, positive battery is placed thereon, which is followed by positive battery when the register 70 reaches 13, and also by positive battery when the register reaches 14, and finally negative battery when the thousands register reaches position 15. Thus, in positions 11, 12, 13, 14 and 15, four positive impulses 75 followed by a negative impulse are placed upon the printer control circuit so that the relay 720 will be energized four times and the relay 721 once. By reference to the code given above, it will be seen that this combination of impulses will cause the printing 80 of the numeral 11.

Upon the first energization of the relay 720 a circuit is established for the selecting magnet 730, which extends from battery, inner armature of the relay 720, closed contact 725 of the distributor switch selecting magnet 730 to ground at the back contact and armature of the clear-out relay 738. The power magnet 722 of the distributor switch is also energized when either of the relays 720 or 721 is energized over a circuit which extends from battery through the armature of either of the relays 720 or 721, conductor 723, magnet 722 to ground. 90 Due to the successive operations of the magnet 722, the set of contacts 725 to 729 are successively closed and opened, only one contact of the set being closed at any one time. This is in accordance with the Patent No. 1,215,917, issued February 13, 1917, to Oscar A. Danielson, hereinbefore mentioned. It is thought that it will be easily understood that the next three energizations of the relay 720 will cause the energization of the selecting magnets 731, 732 and 733. When in response to the last 95 impulse, which is negative, the relay 721 is energized, no circuit is established to the selecting magnets but as the magnet 722 is energized, contact 724 is closed, and the relay 735 is energized over a circuit which 100 extends from battery, left-hand armature and contact of the relay 721, conductor 723, contact 724, relay 735 and the armature 105 and back contact of the clear-out relay 738. As soon as the relay 735 is energized, which occurs only after all of the impulses have 110 been sent to the printer and the selecting magnets have been energized, and the selecting disks (not shown) have been positioned, a circuit is established for the release magnets 739, which circuit extends from battery through magnets 739, inner armature and contact of the relay 735, winding of 115 relay 735, back contact and armature of the clear-out relay 738, to ground. The operation of the release magnet closes a circuit for the start magnet 740 and at the 120 same time permits the selected lever to 125 130

operate, which it will be assumed for the purpose of illustration is the one indicated at 741. The circuit for the start magnet 740 may be traced from battery through 5 contact 736, magnet 740, armature and contact of the release magnet, contact and armature of the clear-out relay 738 to ground. The operation of the start magnet releases the type shaft indicated at 742 and permits the type wheel to rotate until the selected lever 741 engages the stop arm 743 carried by the type holder. As soon as the stop arm 743 engages with the selected lever 741, the type wheel is in the 10 proper position for printing the selected character, in the case assumed to be the character 11, which is accomplished by the operation of the printing hammer in response to the energization of the magnet 20 745. The printing hammer is not shown nor is the paper carriage, as the specific construction of the printer forms no part of the present invention. As soon as the type wheel is properly positioned a circuit 25 is established for the clear-out relay 738, the space operating relay 744 and the printing magnet 745. This circuit extends from battery and through the clear-out relay 738, right-hand winding of the space controlling relay 744, printing magnet 745, type wheel shaft 742, stop 743, selected lever 741 to ground. The magnet 745 operates to cause the impression of the character represented by the position of the type 30 wheel and relay 744 closes a circuit from the space magnet 746, and a locking circuit for itself, as will be apparent from an inspection of the drawing. The clear-out relay 738 opens the previously traced 35 circuits of the selecting magnets and the various other magnets and relays and restores all of the printing apparatus to normal. As soon as the release magnet is restored the energizing circuit for the relays 40 45 744 and 738 is opened at the lever 741, permitting such relays to release. As soon as the space magnet operates, it opens the locking circuit of the relay 744 and at the same time moves the paper carriage through 50 55 a space in order to present a clean space on the paper for recording the next character.

It will be recalled that as soon as the fifth impulse was sent over the printer control circuit the thousands register was stopped, due to the energization of the No. 0' counting relay, which, in turn, opened the energizing circuit for the relays 412 and 405. The release of the relay 412 closes a 60 circuit to drive the sequence switch 400 into position 11, which circuit extends from battery through the motor magnet of sequence switch 400, contact 401 (position 10), conductor 336, contact 330 (position 10), conductor 337 to the back contact and outer

armature of the relay 412 to ground. As soon as the sequence switch 400 reaches position 11 the locking circuits of the counting relays are opened at the contact spring 490, and such relays are restored to normal. 70 Therefore, in position 11 of the sequence switch 400 a circuit for the relays 412 and 405 is again established, which circuit extends from battery through left-hand winding of the relay 412, contact 436 (position 75 11), conductor 437, contact 318 (position 10), contact 403 (position 11), conductor 404, stepping relay 405, back contact and armature of the number 0' counting relay, conductor 406, front contact and right armature of the relay 303 to ground. The energization of the relay 412 at this time establishes a circuit to drive the sequence switch 400 into position 12, which circuit extends from battery through the motor magnet of 80 85 the sequence switch 400, contact 401 (position 11), conductor 335, contact 333 (position 10), conductor 334, front contact and outer armature of the relay 412 to ground. With the sender sequence switch 400 in position 12 the printer control circuit is again established and extends from conductor 428 through contact 425 (position 12) by way of conductor 422 to the contact springs actuated by the hundreds register. As soon as 90 95 the stepping relay 405 is energized, the No. 4 counting relay will be energized, as in the previous case, and as soon as the relay 412 is energized a circuit is closed for the power magnet 623 of the hundreds register, which 100 circuit extends from battery, contact 638 of the hundreds register, conductor 615, contact 417 (position 12), conductor 437, power magnet 623, back contact and inner armature of the cut-off relay 630, conductor 418, 105 contact 419 (position 12), conductor 335, contact 333 (position 10), conductor 334 to the front contact and outer armature of relay 412. The hundreds register now moves through five additional positions in the same 110 manner as the thousands register moved through five positions under the control of the stepping magnet 405 and the counting relays, the stepping magnet being controlled by register spring 616 in the half or intermediate 115 positions.

As the hundreds register has been set in position 5, the first impulse placed upon a printer control circuit is negative, which is followed by negative in position 6, negative 120 in position 7, positive in position 8 and negative in position 9, which is the impulse combination necessary to select and cause the recording of the character 5. Consequently, there will be three energizations of the relay 125 721, followed by an energization of the relay 720 and by an energization of the relay 721. It is thought that it will be obvious from the description given of the operation of the printer in printing the character 11 that this 130

combination will result in the energization of the selecting magnet 733 and the selection of the suitable selecting lever 741 to cause the printing of the character 5. After the 5 hundreds register has passed through the five extra positions, the No. 0' relay is energized, and the relays 412 and 405 are de-energized. The previously traced circuit for the power magnet 623 is opened when the 10 relay 412 releases, and, furthermore, the release of the relay 412 closes a circuit to drive the sequence switch 400 into position 13, which circuit extends from battery to the motor magnet of sequence switch 400, contact 401 (position 12), conductor 336, contact 330 (position 10), conductor 337, back contact and outer armature of the relay 412 to ground.

As soon as the sequence switch 400 reaches 20 position 13 the counting relays are restored to normal, and the energizing circuit for the relays 412 and 405 is again established. This circuit is the same as that in which these relays have been previously energized and 25 will not be again traced. However, as soon as the relay 412 is energized, a circuit is established to drive the sequence switch 400 into position 14, which circuit extends from battery to the motor magnet of the sequence 30 switch 400, contact 401 (position 13), conductor 335, contact 333 (position 10), conductor 334 to the front contact and outer armature of the relay 412 to ground.

In position 14 of the sequence switch 400 35 a circuit is established for the motormagnet 624 of the tens register, which circuit extends from battery, contact 440 (position 14), conductor 413, motor magnet 624, armature and back contact of the relay 631, conductor 418, contact 419 (position 14), conductor 335, contact 333 (position 10), conductor 334, armature and contact of the relay 412 to ground. A circuit is also established for the No. 4 counting relay by way 45 of the contact 420 and the armature and contact of the stepping relay 405, and, as in the case of the thousands register, when the tens register has passed through five positions the relay 405 is shunted that number of 50 times at the spring 617, the No. 0' counting relay is energized, opening the energizing circuits for the relays 412 and 405, and, consequently, the energizing circuit of the power magnet 624.

55 It will be observed as the tens register moves through positions 4, 5, 6, 7 and 8, the following code of impulses are placed upon the conductor 423 by the tens register springs and, by way of the contact 425 in 60 position 14, are impressed upon the printer control circuit: negative, negative, negative, negative, positive. This particular combination of impulses will cause the printer to operate as before described to print the 65 character 4. When the relay 412 is deener-

gized, due to the operation of the No. 0' counting relay, a circuit is established to drive the sequence switch 400 into position 15, which circuit extends from battery through motor magnet of the sequence 70 switch 400, contact 401 (position 14), conductor 336, contact 330 (position 10), conductor 337, back contact and outer armature of the relay 412 to ground.

As the sequence switch 400 leaves position 75 14 the locking circuit for the counting relays is opened at the contact 490, and when the No. 0' relay releases its armature, the previously traced circuit for the relays 412 and 405 is again established. Relay 412 80 when energized closes a circuit to drive the sequence switch 400 into position 16, which circuit extends from battery through motor magnet of the sequence switch 400, contact 401 (position 15), conductor 335, contact 333 (position 10), conductor 334, front contact and outer armature of the relay 412 to ground. In position 16 of the sequence switch 400 with the relays 412 and 405 energized, the number 4 counting relay is energized, and a circuit is established for the motor magnet 625 of the units register, which circuit extends from battery, contact 440 (position 16), conductor 414, magnet 625, back contact and inner armature of the 95 relay 632, conductor 418, contact 419 (position 16), conductor 335, contact 333 (position 10), conductor 334, front contact and outer armature of the relay 412 to ground. The units register thereupon begins to rotate 100 and continues to rotate until, due to five shuntings of the stepping relay 405, the No. 0' relay is energized, opening the circuit of the relays 412 and 405, and, consequently, the circuit of the power magnet 625. As it 105 was assumed that the units register was set in position 9, the following series of impulses is impressed upon the conductor 424 and through the units register springs by way of contact 425 (position 16) on the 110 printer control circuit as the units register moves from position 9 to position 13: negative, positive, positive, positive, positive. These impulses passing over the printing control circuit operate the printer as before 115 described to cause the selection and printing of the character 9. The release of the relay 412, in addition to opening the circuit of the power magnet of the units register, also drives the sequence switch 400 into position 120 17 over a circuit which extends from battery through motor magnet of the sequence switch 400, contact 401 (position 16), conductor 336, contact 330 (position 10), conductor 337, back contact and outer armature of the relay 412 to ground.

As the sequence switch 400 leaves position 125 12 the previously traced locking circuits for the counting relays are opened at the contact 490, and the circuit previously traced 130

for the relays 412 and 405 is again established. The energization of the relay 412 results in driving the sequence switch 400 into position 18 over a circuit which extends 5 from battery through motor magnet of the sequence switch 400, contact 401 (position 17), conductor 335, contact 333 (position 10) conductor 334 to the front contact and outer armature of the relay 412 to ground. As 10 soon as the sequence switch 400 reaches position 18, the number 4 counting relay is energized over the contact 420 and the armature and contact of the relay 405. The circuit for the power magnet 626 of the station 15 register is also established, which circuit extends from battery to the contact 440 (position 18), conductor 415, magnet 626, back contact and armature of the relay 633, conductor 418, contact 419 (position 18), conductor 335, contact 333 (position 10), conductor 334, front contact and outer armature of the relay 412 to ground. The station 20 register begins to rotate and as it rotates shunts the stepping relay 405 at the 25 spring 619. After five shuntings of the relay 405 the No. 0' counting relay is energized, causing the release of the relays 405 and 412, and, consequently, the opening of the circuit of the power magnet 626. The 30 station register in passing from either positions 1 or 10, in which it is assumed to be set, places the following combination of impulses on the conductor 426 through the units register springs and by way of contact 35 427 (position 18) on the printer control circuit: negative, positive, negative, positive, negative. The printer will operate in the normal manner in response to this code of impulses to record the character J. However, 40 the printer is provided with a special contact or set of contacts, one of which is indicated at 736, which are operated by suitable selecting levers whenever the series of impulses necessary to cause the printing of any 45 station is impressed upon the printer control circuit so that as the impulses representing the station are the last sent, it will be obvious that contact 736 will be operated at the end of the printing operation, that is, after 50 the complete number has been printed. This contact 736 when operated closes a circuit for the magnet 747 from battery through the contact 736, contact 748, relay 747 to ground. This magnet may be utilized 55 to operate suitable cutting apparatus (not shown) to sever the tape upon which the number has been printed. The contact 736 when operated also opens the previously traced locking circuit for the relay 702. Before 60 considering, however, the effect of the release of the relay 702, the operation at the sender which may be going on at the same time will be considered.

Remembering that in position 18 of the 65 sequence switch 400 the circuits for the re-

lays 412 and 405 were open due to the energization of the 0' counting relay, the release of the relay 412 at this time closes a circuit to move the sequence switch 400 from position 18 into position 1, which circuit extends from battery, through the motor magnet of sequence switch 400, contact 401 (position 18), conductor 336, contact 330 (position 10), conductor 337, back contact and outer armature of the relay 412, to ground. As the sequence switch reaches position 18, the locking circuits for the counting relays are opened when all of the apparatus individual to the registering and controlling equipment is restored to normal, it being observed, however, that the registers have no normal position, remaining in the position in which they were set until again taken for use. With the sequence switch 400 in position 1 and the sequence switch 300 in position 10, a circuit is established to drive the sequence switch 200 into position 14, which circuit extends from the motor magnet of sequence switch 200, contact 233 (position 11), contact 249 (position 11), conductor 240, terminal 323, brush 322, conductor 321, contact 320 (position 10), contact 419 (position 1), conductor 350, contact 314 (position 10) to ground.

As the sequence switch 200 moves out of position 11, the holding circuit for the relay 303 is opened at contact 219, whereupon the relay 303 deenergizes and closes a circuit to drive the sequence switch 300 into position 15, which circuit extends from battery, through the motor magnet of sequence switch 300, contact 331 (position 10), back contact and right-hand armature of the relay 303 to ground.

In position 14 of the sequence switch 200 and position 15 of the sequence switch 300, a circuit is closed to drive the listening key sequence switch 100 out of position 7 into position 11, which circuit extends from battery through the motor magnet of sequence switch 100, contact 102 (position 7), conductor 115 to the point marked X', from thence to the point marked X' in Fig. 3, back contact and left-hand armature of the relay 340, conductor 338, contact 426 (position 1), conductor 339, contact 304 (position 15), right-hand armature and back contact of relay 303 to ground. While sequence switch 100 is passing through positions 7₃ to 10₁ a circuit is completed from battery, contact 327 (position 15), relay 340, contact 341 to the point marked W in Fig. 3 to the point marked W in Fig. 1, contact 117 (positions 7₄ to 10₂) to ground. The relay 340 when energized places ground upon the contact 341 through its right-hand armature and thus locks up. At its left-hand armature the relay 340 closes a circuit from battery, through the down-drive magnet 342 of the cord finder, front contact and right-hand 130

armature of the relay 340, conductor 338, contact 426 (position 1), conductor 339, contact 304 (position 15), back contact and right-hand armature of the relay 303 to ground. The cord finder is returned to normal, and when the brush 343 makes contact with the normal contact Y, a circuit is closed to drive the sequence switch 300 out of position 15 into position 18, which circuit extends from battery, through the motor magnet of the sequence switch 300, contact 305 (position 15), contact Y, brush 343 to ground.

Returning now to the operation initiated by the release of the relay 702 at the printer.

The release of the relay 702 reestablishes the circuit of the magnet 701, so that if a relay 800 individual to another trunk should be energized, the switch 700 will be started to hunt for such trunk. In addition to this the release of the relay 702 opens a shunt about the relay 805, permitting it to operate. The energizing circuit for relay 805 now extends from battery, through the normal contacts of the relay 803, relay 802, left-hand armature and back contact of relay 802, upper winding of the relay 805 to ground. The energization of the relay 805 results in the energization of the relay 806, whose circuit extends from battery, through relay 806, through winding 807 of the repeating coil, front contact and upper armature of the relay 805, conductor 801, terminal 242, brush 243, contact 227 (position 14), conductor 251, contact 117 (position 11), conductor 252, through the winding 253 of the repeating coil to ground. The energization of the relay 806 establishes a circuit for the relay 808, which circuit extends from battery, through the relay 808, back contact and armature of the relay 809, front contact and armature of relay 806 to ground. The relay 806 when energized also establishes a circuit for the guard lamp 821, which circuit extends from battery, lamp 821, through the right-hand armature and back contact of the relay 810, back contact and left-hand armature of the relay 811, back contact and armature of the relay 809, the armature and contact of relay 806 to ground. The illumination of the lamp 821 notifies the operator that there is a call on that trunk, and the operator observing the number of the required line as printed by the printer, inserts the plug indicated at 812 in the jack indicated at 822 which, it will be assumed, is the jack of the desired line. The operator is enabled to identify the particular trunk from the trunk number printed adjacent the telephone number in the operation of the printer.

The testing of the line takes place in the usual manner, and assuming that the line is idle and the plug has been inserted in the

jack, the relay 813 is energized in series with the cut-off relay in the usual manner. The energization of the relay 813 establishes a circuit for the relay 811, which circuit extends from battery to the lower armature and front contact of the relay 813, conductor 823, right-hand winding of the relay 811 to ground. The energization of the relay 811 results in the energization of the relay 890. The relay 890 is energized over a circuit which extends from battery through right-hand armature and contact of the relay 811, conductor 815 to the right armature and front contact of the relay 808 and through the winding of the relay 890 to ground. The relay 890 is energized in this circuit, and prepares a circuit for relay 816. Relay 816 is then energized in parallel with relay 890 and closes a circuit for the relay 809 in series with the relay 816, but the relay 809 is prevented from energizing as it is short-circuited at the right-hand armature and contact of the relay 890. Before considering the energization of the relay 817, it will be observed that the relay 816 establishes a circuit for the relay 803, which circuit extends from battery to the right-hand armature and contact of relay 816, the relay 803, outer armature and back contact of the relay 809 to ground. The relay 803 when energized closes a holding circuit for the relay 805 and opens a previously traced circuit for the relay 802. This holding circuit extends from battery to the armature and contact of the relay 803, lower winding of the relay 805 to ground.

The energizing circuit for the relay 817, referred to above, extends from battery through the relay 817, armature and back contact of the relay 818, back contact and armature of the relay 823, back contact and left-hand armature of relay 810, front contact and left-hand armature of the relay 811, back contact and inner armature of the relay 809, contact and armature of the relay 806 to ground. The energization of the relay 817 connects ringing current to the line through relay 823, which is the ordinary cut-off relay. As soon as the called subscriber answers, the resistance of the ringing circuit is reduced to such an extent that the ringing cut-off relay 823 is energized, which relay when attracting its armature permits the relay 818 to be energized in series with the relay 817 over the original energizing circuit of the relay 817. As soon as the relay 818 is energized, it short-circuits the relay 817 by connecting battery at its armature and front contact between the relay 817 and the ground at the armature of the relay 806. When the called subscriber answers the supervisory relay 819 is energized and the call may be supervised in the usual manner. As the super-

vision of the call forms no part of the present invention it will not be described further.

At the termination of the call in response to a suitable signal when the A operator removes the plug 203 from its jack, the apparatus associated with the connecting circuit in Fig. 2 will be restored to normal in the usual manner, which will result in the deenergization of the relay 806 as the circuit previously traced for such relay will be opened. From a consideration of the circuits previously traced in extending the various operations associated with the trunk at the B operator's position, it will be apparent that as a result of the release of relay 806 the relays 808 and 890 will be released. As soon as the relay 890 is released the short circuit is removed from the relay 809, which permits relay 809 to energize. With the release of the relay 806 the relay 818 releases, and, due to the energization of the relay 809, the relay 803 is released as the energizing circuit therefor is opened at the outermost armature and back contact of the relay 809. The release of the relay 803 opens the previously traced holding circuit for the relay 805. With the relay 805 released and relay 803 released, it is obvious that another call can be extended to the trunk and that the printer can be associated therewith irrespective of whether or not the B operator has taken down a connection by removing the plug 812 from the jack 822. If the B operator removes the plug 812 from the jack 822 such action will result in the release of the relay 813, and, consequently, in the release of the relays 811, 816 and 890. If, however, the B operator fails to take down this connection as soon as the printer has completed its operation in recording the next call on the trunk, relay 802 is energized as before, causing the energization of the relays 805 and 806, such relays being energized over circuits previously traced. The relay 809, however, will be energized so that as soon as the relay 806 is energized, a circuit is established over the relay 810, which circuit extends from battery to the right-hand winding of the relay 810, front contact and armature of the relay 809, right armature and contact of the relay 806 to ground. The energization of the relay 810 at this time connects the interrupter 824 to the circuit of the lamp 821, which lamp will intermittently flash, notifying the B operator that another call has been connected to the particular trunk and that the number of the desired line has been recorded in the printer.

The system, as above mentioned, is adapted to print numbers having five digits and an arbitrary character or letter representing the particular station. In case a num-

ber represents a direct line an arbitrary symbol such as a star may be printed after the number, or the printer can be arranged to space without printing in case the combination of impulses representing a direct line is received. It will be noted that in order to print the five digit number and the stations there is a printing operation for the thousands, hundreds, tens, units digits and for the station character, making five operations in the printer in all for a normal call. It is obvious that if the number to be printed should happen to be, as is often the case, merely a two digit number, such, for example, as 60, it will be of advantage and a considerable saving in time to automatically eliminate the thousands and hundreds printing operation. In other words, if there is an initial zero in the number it is of advantage to eliminate entirely the printing operation corresponding to the initial zero digit. This result is obtained in the system disclosed by the following arrangement. It will be observed that the thousands register, shown in Fig. 6, is provided with a special contact indicated at 634, which is closed only in a zero position, and similarly that the hundreds register is provided with a contact 640 which is closed only in the zero position.

In order to avoid the necessity of depressing a key if the digit is zero, which may be the case with any digit except those representing the stations, the thousands, hundreds, tens and units are provided with normally closed contacts 650, 651, 652 and 653; these contacts are arranged to be opened by the depression of any key other than the zero key and when no key is depressed serve to connect ground on the zero contact spring of the register to position such register in zero position. The ordinary zero key can also be arranged when depressed to connect ground on the zero contact spring of the register so that in setting up all numbers on her keyboard except those having zero for the initial digit or digits, the operator may depress a key for each digit.

Let it be assumed that the thousands digit of the required number is zero and the other digits are as before considered, making the number 0-5-4-9-J, in which case, in response to the depression of the zero key, or what amounts to the same thing in the arrangement disclosed if no key is depressed, the thousands register is set in position 0. Therefore, when the relay 412 energizes in position 9, the sequence switch 400, as before described, is moved into position 10. As soon as the sequence switch 400 reaches position 10 a circuit will be closed for the No. 0' counting relay, which circuit extends from battery through the Nos. 0 and 0' counting relays in series by way of con-

ductor 441, contact 442 (position 10), conductor 429, thousands register spring 634 (position 0), to ground. The thousands register will not be started in motion when 5 the sequence switch 400 reaches position 10, for the reason that it will be recalled that the energizing circuit for the magnet 622 obtained battery through register spring 613 which is open in position 0. As the 10 result of the energization of the 0' relay, the relay 412 is deenergized in identically the same manner as though the register had moved through the five additional positions and the sequence switch 400 is driven into 15 position 11. Thus, the register is not moved and the sequence switch 400 is driven through two positions without any impulses being placed upon the printer control circuit. If both the thousands and hundreds 20 registers are set in position 0, the sequence switch 400 will move from position 9 to position 11 without starting the thousands register or placing the impulses upon the printer control circuit, in the manner above 25 described, and the spring 640 of the hundreds register will operate to energize the No. 0' counting relay in the same manner as the spring 634 of the thousands register. Also, unless the thousands register has been 30 set in some other position than zero, the power magnet of the hundreds register will not be energized, as the battery therefor is connected while the spring 613 of the thousands register is out of position 0 and while 35 the spring 613 is in position 0, or direct from the spring 638 if the hundreds register is in any position except zero. Therefore, it will be apparent with the hundreds and thousands registers in the zero positions, the 40 sequence switch 400 will move from position 9 to position 11 and from position 11 to position 13 without placing any impulses on the printer control circuit and without moving either of the thousands or hundreds reg- 45 isters from the positions in which they are set. On the other hand, if the initial thousands register is in any position but zero, and the hundreds digit is zero, the closure of the spring 640 in position 0 will be with- 50 out effect on the counting relays, as the circuit for the No. 0' counting relay previously traced will be open at spring 634 of the thousands register and battery will be placed upon the hundreds register, the 55 power magnet 623 through spring 613 in any position except zero and spring 638 in zero. Therefore, in the system disclosed, in case the initial thousands or initial hundreds digits are zero, the corresponding opera- 60 tion of the printer will be automatically eliminated.

What is claimed is:

1. In a telephone exchange system, the combination of an operator's position, a 65 plurality of connecting circuits, a recording

device, means for automatically associating the recording device with a connecting circuit which has been taken for use, and means for recording a character to identify the particular connecting circuit with which the 70 recording device has been associated.

2. In a telephone exchange system, the combination of an operator's position, a connecting circuit, a call number displaying device adapted to be associated therewith, means for controlling such displaying device over such connecting circuit to display a telephone number, a signal individual to such connecting circuit controlled by such recording device to indicate to an 80 operator that the recording device has completed its operation.

3. In a telephone exchange system, the combination at an operator's position of a connecting circuit, a call number displaying 85 device adapted to be connected therewith, means for controlling such displaying device over such connecting circuit, means controlled by the displaying device when it has completed its operation for rendering 90 such connecting circuit non-connectible to a displaying device.

4. In a telephone exchange system, the combination of an operator's position, a connecting circuit adapted to be used in establishing a connection between a called and calling subscriber's lines, a call number displaying device, means for associating such displaying device with such connecting circuit, means for controlling such displaying 100 device over such connecting circuit, means rendered operative when the displaying device has completed its operation for disconnecting it from the connecting circuit and for rendering such connecting circuit non- 105 connectible to such displaying device, and means rendered operative by the breaking down of the connection extended over such connecting circuit for permitting such connecting circuit to be again associated with 110 such displaying device.

5. In a telephone exchange system, the combination at an operator's position of a connecting circuit, a call number displaying device adapted to be controlled thereover, 115 means for associating said displaying device with said connecting circuit, means controlled from such displaying device for disconnecting the displaying device from the connecting circuit and for closing such connecting circuit for conversational purposes, and means controlled by the disconnection of said connecting circuit to open the connecting circuit and to render it selectable 120 to the displaying device.

6. In a telephone exchange system, an operator's position, a connecting circuit thereat adapted to be utilized in establishing a connection between a calling and a called line, a call number displaying device, 130

- means for associating the displaying device with the connecting circuit, means for disconnecting said displaying device from the connecting circuit, and means permitting 5 such displaying device to be again associated with the connecting circuit before the connecting circuit is completely restored to normal.
7. In a telephone exchange system, a connecting circuit, a call number displaying device adapted to be associated therewith, means controlled by said displaying device for actuating a signal associated with a connecting circuit to indicate that the displaying device has completed its operation, means for changing the character of said signal in case the recording device has displayed a subsequent call before the connecting circuit is entirely restored to normal.
- 10 8. In a telephone exchange system, a plurality of operators' positions, a connecting circuit extending therebetween, a controlling device at one operator's position, a recording device at another operator's position controlled thereby, adapted to record the designation of a telephone line, means forming a part of such recording device operable at the termination of the operation of the controlling device for severing the record 15 produced in such recording device.
9. In a telephone exchange system at an operator's position, a connecting circuit adapted to be utilized in extending the connection from a calling to a called line, a call number displaying device, an automatic switch associated therewith for selectively connecting such displaying device with a connecting circuit, means operable upon the termination of the operation of the displaying device to disconnect the device from the connecting circuit and to render such connecting circuit non-selectable in such automatic switch, and means controlled by the 20 partial breaking down of the connection for rendering such connecting circuit again selectable in such automatic switch.
10. In a telephone exchange system, an operator's position, a plurality of connecting circuits thereat, a less number of call 25 number displaying devices, a line and cut-off relay associated with the connecting circuit, means for operating said line relay when a call is extended to the connecting circuit, such line relay controlling the association of a displaying device with such connecting circuit, means controlled from the displaying device for operating such cut-off relay to render the connecting circuit non-connectible to a displaying device, and 30 means controlled by the release of said connecting circuit for releasing such cut-off relay.
11. In a telephone exchange system, an operator's position, a connecting circuit 35 thereat for establishing a connection to a called line, a signal associated therewith, an indicating device adapted to be associated with the connecting circuit, means controlled upon the completion of the operation of such indicating device to cause the display of said signal, means for disabling such signal when the connecting circuit is associated with the called line, and also to change the character of such signal if the indicating device is again operated before the connecting circuit is disconnected from the called line.
12. In a telephone exchange system, an indicating device for indicating the designation of a telephone line, a controlling equipment to control the operation of such indicating device comprising a register which has no normal position, a manually operable device adapted to be operated in accordance with the designation of the line, 40 means for driving said register to a position determined by the operation of such manually operable device, means for moving said register through a definite additional number of positions, and means controlled by such register in such further movement for controlling the operation of the indicating device.
13. In a telephone exchange system, a device for indicating the designation of a telephone line, a registering and controlling equipment, a connecting circuit extending between such equipment and such indicating device, a plurality of registers adapted to be set in positions corresponding to the designation of the line which it is desired to indicate, means for successively driving such registers through a definite number of additional positions, and means controlled by such registers in such additional movement for operating such indicating device.
14. In a telephone exchange system, an "A" operator's position, a "B" operator's position, a call number indicating device at such B operator's position, a registering and controlling equipment at such "A" operator's position, manually operable means at such "A" operator's position for setting the registers of the registering and controlling equipment in positions corresponding to the designation of a telephone line, means controlled by the set position of certain of said registers for extending a connection to such "B" operator's position, means for driving other of such registers through a definite number of additional positions beyond the set position thereof, means controlled by such registers in their additional movement for controlling the indicating device at such "B" operator's position to indicate the number of the desired line.
15. In a telephone exchange system, a call number indicating device, a controlling means therefor comprising a plurality of registers adapted to be set in accordance

- with the designation of a line which it is desired to record, a set of counting relays, means for energizing a certain pair of such counting relays for starting a register in motion from a set position, means controlled by the movement of such register to operate successive pairs of such counting relays, means controlled by the operation of the last pair of the counting relays for stopping the movement of the register, and means controlled by the movement of the register for impressing controlling impulses on a circuit extending to such indicating device to operate such recording device. 5
16. In a telephone exchange system, a call number displaying device, a registering and controlling equipment comprising means for registering the designation of a called line, controlling means, means for placing such controlling means under the control of the registering means for the purpose of governing the establishment of a circuit between the equipment and the call exhibiting device. 10
- 20 and means for subsequently placing such registering means under the control of the controlling means for the purpose of governing the operation of such displaying device. 25
17. In a telephone exchange system, a call number displaying device, a registering and controlling equipment comprising registering means and controlling means, means for placing such registering means under the control of such controlling means, a control circuit, an automatic switch for associating said control circuit with said call number displaying device, and means variably controlled from such registering 30 means for governing the operation of the call displaying device over said control circuit. 35
18. In a telephone exchange system comprising automatic switches, a call displaying device and a registering and controlling equipment, such registering and controlling equipment comprising a plurality of registers and a counting device, means for setting such registers to register the designation of a called line, means for placing such counting device under the control of certain of such registers to control such automatic switches for the purpose of establishing a control circuit from such equipment to the 40 call displaying device, means for placing other of such registers under the control of such counting device, and means controlled by such other registers for impressing impulses on such control circuit to govern the operation of such recording device. 45
19. In a telephone exchange system, automatic switches, a call displaying device and a registering and controlling equipment, such registering and controlling equipment comprising a plurality of registers adapted 50
- 55 to be set to register the designation of the called line, a counting device and a stepping relay, a fundamental circuit including such stepping relay extending between such equipment and an automatic switch adapted to be controlled thereby, means controlled by the action of such stepping relay and certain of such registers for operating the automatic switches to extend the connection to such call displaying device, means for establishing a local control circuit in such registering and controlling equipment including such stepping relay for controlling an additional movement of certain of such registers beyond their set position, and 60 means controlled by the movement of such registers beyond their set position for impressing impulses on the control circuit to cause the operation of such call displaying device. 65
20. In a telephone exchange system, automatic switches, a call displaying device and a registering and controlling equipment comprising a plurality of registers adapted to be set in accordance with the designation 70 of a required line, means controlled by the set position of certain of such registers for controlling such automatic switches, means for imparting a movement to other of such registers beyond their set position, and 75 means controlled by such additional movement to control the operation of the call displaying device. 80
21. In a telephone exchange system, automatic switches, a call displaying device, a registering and controlling equipment comprising a plurality of registers and a common counting device, means for operating such counting device under the joint control 85 of certain of such registers, and an automatic switch for the purpose of extending the connection to such call displaying device, means for operating other of such registers, means controlled by the operation of such registers to operate the counting device, means controlled by the counting device to terminate the operation of such registers, and means controlled by such registers for governing the operation of the 90 call displaying device. 95
22. In a telephone exchange system, a call number displaying device, a control circuit for such device, a register adapted to be set to represent the designation of the call to be displayed, means for automatically driving such register through a definite number of additional positions beyond its set position, and contact springs operated by such registers in such additional movement for impressing impulses on such control circuit. 100
23. In a telephone exchange system, a registering and controlling equipment for controlling the operation of a call number registering device comprising a multi-position 105
- 110
- 115
- 120
- 125
- 130

- register, a plurality of keys, means controlled by the operation of any one of such keys to set such register in a definite position, and means controlled by the joint operation of more than one key to set such register in another definite position, and means controlled by the set position of the register to control such call number displaying device.
24. In a telephone exchange system, a registering and controlling equipment for controlling the operation of a call number displaying device comprising a multi-position register having no normal position, a plurality of keys, means controlled by a single one of such keys for setting the register in either one of two alternative positions, and means controlled by the set position of the register in either of such positions to control identical operations in such call displaying device.
25. In a telephone exchange system, a call number displaying device, a registering and controlling equipment comprising a multi-position register, a plurality of digit keys, means for setting such register in certain positions in response to the operation of one of such digit keys, a master key, means for setting such register in other positions controlled by the joint operation of the digit key and master key, and means controlled by the set position of the register for controlling the operation of such call number displaying device.
26. In a telephone exchange system, a call number displaying device, a registering and controlling equipment comprising a multi-position register, means to set the register in any one of a plurality of positions, means controlled by such register in certain set positions to operate such call displaying device to display a single digit number, and means controlled by such register in other set positions to operate such call number displaying device to display a plural digit number.
27. In a telephone exchange system, a call number displaying device, a controlling equipment adapted to be set in accordance with the number it is desired to display, means in said equipment for normally producing a series of controlling impulses for each digit of the greatest number it is desired to display, and means for automatically eliminating the initial series of impulses when the initial digit of the number which it is desired to display is zero.
28. In a telephone exchange system, a call number displaying device, a registering and controlling equipment, comprising a series of registers adapted to be set in accordance with the digits of the number it is desired to display, means for successively moving said registers from their set positions to control the operation of such displaying device, means for preventing the movement of the initial register of the series from its set position if its set position represents an initial zero digit of the number registered.
29. In a telephone exchange system, a call number displaying device, a registering and controlling equipment comprising a plurality of registers, means for setting such registers in position corresponding to the designation of the number it is desired to display, means for normally moving such registers through an additional number of positions for the purpose of controlling the operation of the displaying device, and means controlled by the set position of one of such registers to prevent it from being moved through such normal additional movement.
30. In a telephone exchange system, a call number displaying device, a registering and controlling equipment comprising a series of registers, means for setting such registers in positions corresponding to the designation of the number it is desired to display, means for normally moving said registers through an additional number of positions for the purpose of controlling the operation of the displaying device, and means controlled by the set position of one register and the set position of the next register in the series for preventing either of such registers from being moved through such additional movement.
31. In a telephone exchange system, a registering and controlling equipment, apparatus controlled thereby, such registering and controlling equipment comprising a multi-position register having no normal position, remaining in the position in which it was last set until again taken for use, a plurality of keys for setting such register in any position, and means operative when such equipment is again taken for use for setting such register in a definite position provided no keys are operated.
32. In a telephone exchange system, a registering and controlling equipment comprising a multi-position register having no normal position, keys for setting such register in any position, means for moving such register from the position in which it was last set to a position normally determined by the operated key, and means for setting such register in a zero position if no keys have been operated.
- In witness whereof we hereunto subscribe our names this 4th day of May A. D. 1917.

AMOS F. DIXON.
FRANK N. REEVES.
